UNITED STATES PATENT OFFICE.

JOHN A. DOUGHERTY, OF ZANESVILLE, OHIO.

FAN DEVICE.

1,300,253.

Specification of Letters Patent. Patented Apr. 15, 1919.

Application filed February 5, 1915. Serial No. 6,304.

To all whom it may concern:

Be it known that I, JOHN A. DOUGHERTY, a citizen of the United States, residing at the city of Zanesville in the county of Muskingum and State of Ohio, have invented a new and useful Fan Device, of which the following is a specification.

My invention relates to improvements in cooling fans and other fans; and the object 10 of my invention is to agitate and circulate the air of an office, room and so forth, in a more extensive and perfect manner than the common fan devices can do.

I attain this object by the mechanism 15 illustrated in the accompanying drawing, in which Figure 1 is a perspective view of my fan device showing the fans so situated, laterally and at the same elevation, and so similarly directed, and so vertically pitched 20 and laterally trained, that their currents combine; and Fig. 2 is a perspective view showing the fans so situated, laterally and at different elevations, and so similarly directed horizontally that their currents combine.

1 represents the stand and 2, the handhold of my fan device; and 3, the arms of equal length as shown in Fig. 1, which support motors 4 and 5 which operate fans 6 30 and 7, which are situated at the same elevation; fan 6 being elevated and fan 7 being depressed in pitch in relation to their common horizontal plane; and both fans being so similarly directed and so laterally trained, 35 that the elevated and depressed currents (which are spiral currents, formed by the lateral air-pressure upon the radially, circumferentially and axially directed air from the fans) join; and, when the fans rotate 40 in the same direction, their joint action is to cause their primary currents more or less to oppose and resultantly to divert each other, and correspondingly to force the joint current radially outward; and which differently 45 pitched and laterally trained primary, and modified and radially enlarged resultant currents more thoroughly and evenly distribute the moving air through the space to be fanned or cooled.

When the fans rotate in opposite directions, the nearest and farthest parts of the two currents, have substantially reversed resultant effects upon each other.

And when the fans are situated at different elevations, their currents impinge eccentrically, thereby producing a modified resultant current, substantially like the one above described.

8 and 9 represent the arms of unequal length as shown in Fig. 2. Arm 8 supports 60 motor 10 and arm 9 supports motor 11. Motor 10 operates fan 12, and motor 11 operates fan 13; and when they rotate in the same direction, their currents affect each other, producing resultant modifications of 65 substantially the same currents as those produced by fans 6 and 7 as above described.

I claim—

1. The combination with a fan device, of a single stand combined with two arms in 70 combination with two fans, one fan being combined with one of said arms and the other fan being combined with the other of said arms, said fans being so directed and trained that their currents combine, substantially as described.

2. The combination with a fan device, of a single stand combined with two arms in combination with two fans; one of said fans being combined with one of said arms, and 80 the other of said fans being combined with the other of said arms, said fans being so directed and trained that the nearest parts and the farthest parts of their currents combine, substantially as described.

3. The combination with a fan device of a single stand combined with two arms having different elevations, in combination with two fans; one of said fans being combined with one of said arms, and the other fan being 90 combined with the other of said arms; said fans being so situated at different elevations and so directed and trained, that their currents combine, substantially as described.

JOHN A. DOUGHERTY.
